STANDABLE FLEXIBLE CONTAINER WITH STRAW

Justin M. Schmit, 3801 NE. 28th Ave.,
Pompano Beach, Fla. 33064

Filed Apr. 29, 1970, Ser. No. 22,709

Term of patent 14 years

Int. Cl. D9—99

U.S. Cl. D9—194

FIG. 1 is a perspective view of a standable flexible container with straw showing my new design;

FIG. 2 is a front view thereof; and

FIG. 3 is a bottom view thereof.

As the perspective view of FIG. 1 and the front view of FIG. 2 illustrate, the side and top edges of the container side walls come into face-to-face engagement and define fins along the side and top periphery of the container. At the bottom of the container, as seen in FIG. 3, these side walls and their bottom edges are widely separated by the container bottom and form a generally elliptical container base. The side walls of the liquid container converge toward each other from near the bottom of the container to joiner at a transversely extending sealing strip immediately below the upper periphery of the container. Above the sealing strip the side walls are in face-to-face relationship, bulging only to accommodate the upper portion of the straw between them.

I claim:
